(57) **CLAIM**

We claim the ornamental design for a packaging container, as shown and described.

DESCRIPTION

FIG. 1 is a front perspective view of a packaging container of the present invention;

FIG. 2 is a front elevation view thereof;

FIG. 3 is a rear elevation view thereof;

FIG. 4 is a right elevation view thereof, the left view being a mirror image thereof;

FIG. 5 is a top view thereof; and,

FIG. 6 is a bottom view thereof.

The broken line showing of packaging container is included for the purpose of illustrating environment and forms no part of the claimed design.
